UNITED STATES PATENT OFFICE.

DAVID H. STEWART, OF KENT, OHIO, ASSIGNOR TO STEWART MACHINE CO., OF KENT, OHIO.

COIN-CONTROLLED APPARATUS.

Application filed January 7, 1924. Serial No. 684,863.

To all whom it may concern:

Be it known that I, DAVID H. STEWART, a citizen of the United States, residing at Kent, in the county of Portage and State of Ohio, have invented certain new and useful Improvements in Coin-Controlled Apparatus, of which the following is a specification.

The invention resides in the provision of certain new and useful improvements in coin controlled apparatus adaptable for use in cooperation with article vending machines.

The invention is particularly adaptable for use in cooperation with that type of vending machine disclosed in the application identified by Serial Number 686,697 in which application a roller type of delivery mechanism is disclosed.

Therefore, it is the object of my present application to provide an improved coin controlled apparatus for use in cooperation with a delivery mechanism in which a full or partial rotation of a part of the mechanism is utilized to effect the vending of the article, which is of a simple and durable structure, inexpensive to manufacture and so constructed and arranged as to assure positive and effective vending of the article under control of the coin or coins of the predetermined values.

The invention further seeks to provide a coin controlled apparatus of the type stated in which means are provided adapting the said apparatus to be controlled by various coin numbers and values to permit the use of said apparatus in cooperation with a single vending machine for vending articles of varying values, as for example, Sunday and daily newspapers.

The invention still further has for its object to provide an apparatus of the type stated in which means are provided for assuring perfect registering alignment of the coin or coins receiving slotways, and other means for permitting a restricting of said slotways for permitting the insertion thereinto of coins of a certain predetermined value only.

With the above and other objects in view, the invention further resides in those novel details of construction, combination and arrangement of parts, all of which will be first fully described, then be particularly pointed out in the appended claims, refer-

ence being had to the accompanying drawings, in which:

Figure 1 is a side elevation of the invention, the casing therefor being shown in section.

Figure 2 is a horizontal section taken on the line 2—2 on Figure 1.

Figure 3 is a vertical cross section taken on the line 3—3 on Figure 1.

Figure 4 is a detail perspective view of the main casting.

Figure 5 is a detail plan view illustrating the coin slotway restricting means.

Figure 6 is a detail section taken on the line 6—6 on Figure 5.

Figure 7 is a diagrammatic fragmentary cross section illustrating a means for automatically closing off the coin slotway.

Figure 8 is a diagrammatic plan view illustrating the cooperative relation of the coin slotway close-off means and the coin slotway portion of the main casting.

In the practical development of my invention I provide a suitable casing 1 for the coin controlled mechanism, which casing includes a side wall, a bottom, a rear wall and a top or cross wall, thus leaving an open side which is adapted to fit up against the side wall 2 of the vending machine with which the apparatus is adapted to cooperate. See for example the machine disclosed in application Serial Number 686,697. In the application mentioned a roller type of delivery mechanism is illustrated, that is, a roller is so positioned within the casing of the vending machine as to engage the foremost one of the newspapers to be vended and adapted, when crank operated as there disclosed, to effect a vending of that foremost paper by a complete rotation of the said roller.

It will be observed that the roller of the delivery mechanism referred to is rotatably mounted in the casing by reason of having its end shaft portions rotatable in suitable bearings formed therefor in the casing walls, one of the said shaft portions being extended into the walls of the casing and adapted to cooperate with the coin controlled mechanism in a manner whereby to permit rotation of the delivery roller only after the insertion of the coin or coins of proper value and the proper operation of the said mechanism as will later be described. This extended shaft portion is, in the present application, indi-

cated by the numeral 3 and a suitable bearing therefor is provided at 4 upon the wall 2 through which the said shaft projects.

It will be observed that the casing 1 is so constructed as to provide an open front through which the mechanism may be adjusted when desired and this open front is closed by a cover door 5 hinged as at 6 to the said casing. This cover door is provided with a reinforce bar 7, for strengthening the same, and the casing may be provided with a supporting flange 8 for supporting the door 5 by reason of which, together with the strengthening bar 7, it is impossible for 10 one endeavoring to tamper with the mechanism within the casing to do so by forcing the door inward.

The casing 1, by reason of its shape and in cooperation with the side wall 2 of the vending machine with which it cooperates and the front cover door 5, provides a compartment within which the coin controlled mechanism is operatively mounted, and also provides space within which may be positioned a coin receiving tray 9 for receiving the coins deposited in the machine in payment for the article to be vended and deposited into the said tray from the coin controlled mechanism in a manner later to be described.

Positioned adjacent the upper portion of the casing 1, and extending thereacross, is a rock shaft 10, the trunnion ends 11 of which have bearings in the casing wall 1 and the vending machine wall 2, and being provided with a lock notch portion 12 adapted to cooperate with the locking lug 13 secured upon the door 5 for locking the said door to the position illustrated in Figure 1 of the drawings. That trunnion end of the rock lock shaft 10 which passes through the wall 2 may be provided with a crank 14 by which the said shaft may be operated for locking or releasing the door in any manner which may be desired, it being understood that while I have illustrated this means for locking the door 5 to the position indicated in Figure 1 of the drawings it should be understood that any locking means may be provided which is suitable for the purposes, as for example any ordinary type of key lock.

The casing 1 includes a top or cross wall portion 15 in which is provided a coin slotway 16, the said cross wall being cut out, as at 17, to permit movement of the several levers later to be described, and this cross wall portion also includes a downward extension 18 which provides a suitable supporting means for a fixed pivot pin 19 adapted to form the pivot for the said movable levers mentioned.

My improved coin controlled apparatus is very simple in construction and comprises comparatively few working parts, all

of which are of simple construction and compactly arranged in a manner whereby it is practically impossible for any of the parts thereof to become broken or dislodged from their operative condition. Of this mechanism the principal part thereof is the main casting member 20 which includes a cylindrical bore 21 for accommodating the extended end of the shaft portion 3.

It will be observed from Figure 3 of the drawings that the said casting 20 is loosely and rotatably mounted upon the end of the shaft extension so as to permit forward rotation of that shaft section independently of the said casting 20. This shaft extension 3 has securely mounted thereupon a ratchet member 22 with which cooperates the spring pawl 23 pivotally secured at 24 upon the casting 20. By reason of the ratchet and pawl connections 22-23 between the casting 20 and the shaft end 3, forward rotation of the said shaft section is permitted independent of the said casting, but any forward rotation of the casting will effect a like forward rotation of the said shaft section in a manner and for a purpose later to be described.

The casting 20 also includes a shaft extension 25 in axial alignment with the bore 21 thereof and which extends through the wall of the casing 1 and is turned down to accommodate an operating crank 26, see Figure 3. The shaft extension 25 of the casting 20 has securely mounted thereupon a ratchet member 27 adapted to cooperate with the spring pawl 28 pivoted at 29 to the wall of the casing 1, which said ratchet and pawl devices cooperate in preventing rotation of the casting 20 in any other manner than forwardly, see Figures 2 and 3. The casting 20 is provided with an annular grooveway 30 in a manner for providing a central hub portion in which the bore 21 is made thereby providing opposing half portions as will be readily apparent from Figures 2, 3 and 4 of the drawings. A coin stripper finger 31 is mounted upon the strengthening bar of the door 5 and projects therefrom between the opposing half portions of the casting 20 and into the annular grooveway 30. A groove is provided in each of the opposing faces of the half portions of the casting 20 in a manner for providing a coin slotway 32, and the slotway is so constructed, and the manner of mounting the casting 20 in cooperation with the ratchet and pawl devices is such, that the said slotway 32 will be normally held in vertical aligning register with the coin slotways 16 formed in the cross wall 15. In each of the flanges aiding in the provision of the slotway 32, is provided a plurality of screw taps 33 provided for accommodating the stop screw 34 insertible into any particular one thereof for providing a stop

for the coin or coins inserted into the coin slotway 16 and which drop therethrough into the coin slotway 32.

By reference to Figure 4 of the drawings it will be observed that the slotway 32, the screw taps 33 and the stop screw 34, cooperate in a manner for stopping the coin or coins in their passage down through the slotway 32 in a manner for causing the uppermost one thereof or the uppermost portion of a single coin, if such be used, to project beyond the top of the casting 20 for a purpose later to be described. It should be here understood that the screw taps 33 are provided so that the screw 34 may be adjusted to various positions for stopping varied single coins or combinations of coins in the manner above described. For example, in Figure 4 is illustrated the adjustment of the devices for stopping two coins, which may be two pennies, a common combination of coin for the vending of a newspaper, it being understood that adjustment is there provided for controlling the apparatus by the use of varied coin values and combinations of coin values as for example by the use of a dime, a nickel, a single penny, two pennies, three pennies or a nickel and two pennies, or any other combination of coins governed by the position of the screw taps 30 so that the uppermost one of the coins will project in the manner illustrated in Figure 4.

A stop lug 35 is secured to and projects laterally from one of the sections of the casting 20 and is adapted to cooperate with a lock lever 36 adapted to prevent backward rotation of the casting 20, the said lever being pivoted at 37 upon the fixed pivot pin 19 and being spring held to the position illustrated in Figure 1, as at 38, and which includes a cam portion 39 adapted to be engaged by the lug 35 as the casting 20 is rotated in the direction of the arrow on Figure 1 for effecting a resetting of the parts to the position indicated in that figure. Another lock lever 40 is provided and cooperates with the said lug 35 in preventing forward rotation of the casting 20 except when coin released from its normal locking position in a manner soon to be described.

A release lever 41 is provided, having an end adapted to be coin engaged, and which extends to a point approximating the plane of the coin slotways 16 and 32 and in position for being engaged by the upwardly projected portion of the coin as indicated in Figures 1 and 4 of the drawings. This lever 41 is pivoted upon the fixed pin 19 and is joined to move with and as an integral part of the lock lever 40 by the cross bridge portion 42 and is also spring held to the position illustrated in Figure 1, as at 38, a stop lug 43 being provided which serves to hold the levers 36, 40 and 41 to the position indi-

cated in the figure referred to, against the tension of the springs 38.

In the operation of my invention one, desiring to purchase a newspaper or other article being vended from the machine of which the wall 2 forms a part, would insert the proper coin or coins into the slotway 16 from whence they would drop into the slotway 32 to be there held by the screw 34 to the position indicated in Figure 1. Before the insertion of the coins it should be understood that forward rotation of the casting 20 would be impossible because of engagement of the lug 35 and the stop lever 40, backward rotation of the said casting being prevented by the ratchet and pawl connections 27—28. The operator then grasping the crank 26 and giving the casting a forward rotative movement, the coin would engage the lever 41 in a manner for forcing it upward against the tension of the springs 38 and in a manner for releasing the lock lever 40 from its locking engagement with the lug 35, it being observed by reference to Figure 1 of the drawings, that sufficient space is provided between these two elements to permit this initial rotation necessary in effecting such release. The casting 20, now being free to rotate one complete revolution before again being engaged by the lock lever 40, may be so rotated carrying with it the shaft portion 3 of whatever rotative delivery mechanism might be provided in the machine with which the apparatus is cooperating. Should any of the coins have a tendency to stick and remain within the coin slotway 32 they will be stripped therefrom by the finger 31 and caused to fall into the receiving tray 9.

As it is common in the use of apparatus of this kind to have persons endeavor, either by reason of an intention to "beat" the machine or by mistake, to insert coins other than those for which the machine is set to receive, I have provided a means for preventing such practice. The said means comprises a pair of coin slotways restricting dogs 44 and 46, each operative independently of the other and having pivotal bearings, as at 46, in an adjacent end of the reinforcing bar 7, as is clearly illustrated in Figures 1, 5 and 6 of the drawings. The bar 7 is cut out, as at 47, to accommodate the heel portions 48, provided one on each of the dogs 44 and 45 and adapted to be engaged by the slide spring 49 adapted to hold the dogs to their extended or retracted positions. The cross wall 15 is provided with suitable recesses 50, one for each of the lugs 44 and 45, and when it is desired to restrict the coin slotway 16 it is only necessary to turn either one or both of the dogs 44 and 45 to the extended position, thus restricting the coin passageway, see Figure 5. For example see Figure 5 in which the slotway is restricted to receive pennies only, thus making

it impossible for a person to insert a nickel by mistake which would possibly result in a jamming of the apparatus. In this case it being necessary to extend one of the dogs, 5 it being understood that should it be desired to restrict this passage for receiving dimes only, both of the dogs might be extended, the spring 49 serving to hold them, either to their extended or retracted positions as stated. 10 I have also provided a means for automatically closing off the coin slotway 16 while the casting is being moved from the normal position illustrated in Figure 1, through its complete revolution and back to 15 that position, so that should a person operating the machine fail to turn the casting a complete revolution necessary for resetting the parts to their normal positions the said means referred to will operate to prevent an 20 insertion of the coin into the machine before the parts are so reset to the normal position, thus preventing any possible jamming of the apparatus or the loss of the coin to the prospective purchaser. In providing 25 this mechanism I provide a cut out portion 51 in the cross wall 15 of the casing 1 in which is pivotally mounted a slotway closing plate 52, as at 53, and which said plate has pendent a finger 54 extending 30 downwardly therefrom into position for engaging one of the slotway forming flanges of the casting 20. See Figures 7 and 8. When the parts of my improved apparatus are at their normal position illustrated in 35 Figure 1 the pendent finger 54 will be engaged by the casting 20 in the manner illustrated in Figure 7 for holding the plate 52 out of cooperative relation with the slotway 16 and in position for permitting the 40 passage of the coin through that slotway and into the slotway 32, it being understood that when the casting 20 has been coin released and rotated in the direction indicated by the arrow on said figure, the finger 54 will 45 be released from engagement therewith, and will be forced by the spring 55 into the position indicated in dotted lines on that figure and for closing off the coin slotway against the insertion of the coin. It will be observed 50 from Figure 7 that the position of the closure plate 52 is such that should a coin be inserted into the slotway when the casting is only partially rotated and the slotway 16 closed off by the plate 52, the coin 55 will only drop down to such a point whereby its uppermost portion will project out of the slotway, in position for being readily engaged by the fingers of the prospective purchaser and withdrawn therefrom. A further forcing downward of the coin by the 60 purchaser will not effect a complete release of the plate such as will permit a dropping in of the coin, the spring 55 serving to force the coin back up again to the position illustrated in that figure. 65

The casing 1 may be secured to the side wall 2 of the vending machine by screws 56 in the manner illustrated in Figures 1 and 2 of the drawing.

It will be observed from Figures 1 and 4 70 of the drawings that the casting 20 is so constructed, and the bore 21 so formed therein, that the center of gravity will be at a point laterally of the axis of that bore and so positioned as to cause a tendency to rotate in 75 a direction opposite that indicated by the arrow on Figure 1, or in a direction tending to hold the stop lug 35 into connection with the lever 36 as is indicated in that figure, thus making it certain that the coin slotways 80 16 and 32 will always be in perfect register.

From the foregoing description, taken in connection with the accompanying drawings, it is thought that the novel details of 85 construction, the manner of operation and the advantages of my invention will be readily understood.

What I claim is:

1. In apparatus of the class described, the combination with a movable part of a vending machine, of a member for moving said movable part, a casing for enclosing said member, the said casing having a coin slotway, the said member having a coin slotway adapted to register with that of the said casing, means for holding said member against forward movement, means on said member for holding the coin inserted into the slotway thereof in a manner whereby the same will project therefrom, means releasable by coin engagement for releasing said forward rotation preventing means, and swingably mounted means mounted on said casing and adapted to be swung into the path of the coin slotway whereby the coin slotway thereof may be restricted to receive certain predetermined coins only. 100

2. In apparatus of the class described, the combination with a movable part of a vending machine, of a casing, a member rotatably mounted in said casing and upon said movable part and so cooperative therewith as to cause forward rotation thereof when said member is rotated but for permitting rotation of said movable part independently thereof, the said casing having a coin slotway, the said member having a coin slotway restricted to permit passage of a coin thereinto in limited degree for causing a portion thereof to project, means for preventing rotation of said member in either direction but permitting a limited amount of movement therebetween, and means operable by engagement therewith of the projected coin portion for releasing said forward rotation limiting means during the limited free movement thereof. 110

3. In apparatus of the class described, the combination with a movable part of a vending machine, of a casing, a member ro- 120

tatably mounted in said casing and upon said movable part and so cooperative therewith as to cause forward rotation thereof when said member is rotated but for permitting rotation of said movable part independently thereof, the said casing having a coin slotway, the said member having a coin slotway restricted to permit passage of a coin thereinto in limited degree for causing a portion thereof to project, means for preventing rotation of said member in either direction but permitting a limited amount of movement therebetween, and means operable by engagement therewith of the projected coin portion for releasing said forward rotation limiting means during the limited free movement thereof, the said member being overbalanced to hold the coin slotways normally in register. 70

10 4. In apparatus of the class described, the combination with a movable part of a vending machine, of a member for moving said movable part, a casing for enclosing said member and being provided with a coin slotway, said member comprising a pair of opposing half portions, a hub joining said half portions, having opposing grooves for providing a coin slotway, and being rotatably mounted in said casing and upon the movable part, a stop lug on said member, a stop lever for preventing backward rotation of said member, a stop lever for preventing forward rotation beyond a limited degree, adjustable stop means on the moving member and cooperative with the coin slotway thereof for intercepting the movement of coins therethrough to cause a portion to project therefrom, and a release lever adapted to be engaged by the projected coin portion during the limited forward rotation permitted for releasing said front lock lever to permit forward rotation of said moving member. 80

20 5. In apparatus of the class described, the combination with a movable part of a vending machine, of a member for moving said movable part, a casing for enclosing said member and being provided with a coin slotway, said member comprising a pair of opposing half portions, a hub joining said half portions, having opposing grooves for providing a coin slotway, and being rotatably mounted in said casing, a stop lug on said member, a stop lever for preventing backward rotation of said member, a stop lever for preventing forward rotation beyond a limited degree, adjustable stop means on the moving member and cooperative with the coin slotway thereof for intercepting the movement of coins therethrough to cause a portion to project therefrom, and a release lever adapted to be engaged by the projected coin portion during the limited forward rotation permitted for releasing said front lock lever to permit forward rotation of said moving member. 90

30 6. In apparatus of the class described, the combination with a movable part of a vending machine, of a member for moving said part, means for locking said member against rotation, coin engaged means for releasing said locking means, a casing for said member and including a coin slotway, the said member including a restricted coin slotway adapted to register with the coin slotway of the casing, coin slotway restricting fingers pivoted in position for being extended across one of the coin slotways for restricting the same to adapt it to receive certain coins only or for being retracted out of the way, and means for engaging said fingers to hold them to their extended or retracted positions. 95

40 7. In apparatus of the class described, the combination with a movable part of a vending machine, of a member for moving said part, means for locking said member against rotation, coin engaged means for releasing said locking means, a casing for said member and including a coin slotway, the said member including a restricted coin slotway adapted to register with the coin slotway of the casing, a yieldably pivoted coin slotway closing plate, means tending to close said plate across the casing coin slotway, and means cooperative with said moving member for holding said closing plate from its slotway closing position. 100

50 8. In apparatus of the class described, the combination with a movable part of a vending machine, of a member for moving said part, means for locking said member against rotation, coin engaged means for releasing said locking means, a casing for said member and including a coin slotway, the said member including a restricted coin slotway adapted to register with the coin slotway of the casing, coin slotway restricting fingers pivoted in position for being extended across one of the coin slotways for restricting the same to adapt it to receive certain coins only or for being retracted out of the way, and means for engaging said fingers to hold them to their extended or retracted positions, a pivoted coin slotway closing plate, means tending to close said plate across the casing coin slotway, and means cooperative with said moving member for holding said closing plate from its slotway closing position. 105

60 9. In apparatus of the class described, the combination with a movable part of a vending machine, of a member for moving said part, means for locking said member against rotation, coin engaged means for releasing said locking means, a casing for said member and including a coin slotway, the said member including a restricted coin slotway adapted to register with the coin slotway of the casing, coin slotway restricting fingers pivoted in position for being extended across one of the coin slotways for restricting the same to adapt it to receive certain coins only or for being retracted out of the way, and means for engaging said fingers to hold them to their extended or retracted positions, a pivoted coin slotway closing plate, means tending to close said plate across the casing coin slotway, and means cooperative with said moving member for holding said closing plate from its slotway closing position. 110

70 10. In apparatus of the class described, the combination with a movable part of a vending machine, of a member for moving said part, means for locking said member against rotation, coin engaged means for releasing said locking means, a casing for said member and including a coin slotway, the said member including a restricted coin slotway adapted to register with the coin slotway of the casing, coin slotway restricting fingers pivoted in position for being extended across one of the coin slotways for restricting the same to adapt it to receive certain coins only or for being retracted out of the way, and means for engaging said fingers to hold them to their extended or retracted positions, a pivoted coin slotway closing plate, means tending to close said plate across the casing coin slotway, and means cooperative with said moving member for holding said closing plate from its slotway closing position. 115

80 11. In apparatus of the class described, the combination with a movable part of a vending machine, of a member for moving said part, means for locking said member against rotation, coin engaged means for releasing said locking means, a casing for said member and including a coin slotway, the said member including a restricted coin slotway adapted to register with the coin slotway of the casing, coin slotway restricting fingers pivoted in position for being extended across one of the coin slotways for restricting the same to adapt it to receive certain coins only or for being retracted out of the way, and means for engaging said fingers to hold them to their extended or retracted positions, a pivoted coin slotway closing plate, means tending to close said plate across the casing coin slotway, and means cooperative with said moving member for holding said closing plate from its slotway closing position. 120

90 12. In apparatus of the class described, the combination with a movable part of a vending machine, of a member for moving said part, means for locking said member against rotation, coin engaged means for releasing said locking means, a casing for said member and including a coin slotway, the said member including a restricted coin slotway adapted to register with the coin slotway of the casing, coin slotway restricting fingers pivoted in position for being extended across one of the coin slotways for restricting the same to adapt it to receive certain coins only or for being retracted out of the way, and means for engaging said fingers to hold them to their extended or retracted positions, a pivoted coin slotway closing plate, means tending to close said plate across the casing coin slotway, and means cooperative with said moving member for holding said closing plate from its slotway closing position. 125

100 13. In apparatus of the class described, the combination with a movable part of a vending machine, of a member for moving said part, means for locking said member against rotation, coin engaged means for releasing said locking means, a casing for said member and including a coin slotway, the said member including a restricted coin slotway adapted to register with the coin slotway of the casing, coin slotway restricting fingers pivoted in position for being extended across one of the coin slotways for restricting the same to adapt it to receive certain coins only or for being retracted out of the way, and means for engaging said fingers to hold them to their extended or retracted positions, a pivoted coin slotway closing plate, means tending to close said plate across the casing coin slotway, and means cooperative with said moving member for holding said closing plate from its slotway closing position.
